UNITED STATES PATENT OFFICE.

FRANK E. MERKLINGER AND SAMUEL R. LIMERICK, OF PHILADELPHIA, PENNSYLVANIA, ASSIGNORS TO THE BALDWIN LOCOMOTIVE WORKS, OF PHILADELPHIA, PENNSYLVANIA, A CORPORATION OF PENNSYLVANIA.

DIE USED IN THE MANUFACTURE OF HORSESHOES.

Application filed May 5, 1922. Serial No. 558,574.

To all whom it may concern:

Be it known that we, FRANK E. MERKLINGER and SAMUEL R. LIMERICK, citizens of the United States, residing in Philadelphia, Pennsylvania, have invented certain Improvements in Dies Used in the Manufacture of Horseshoes, of which the following is a specification.

Our invention relates to certain improvements in dies used for punching and straightening horse shoes, and for bending the toe clips of the shoes.

The object of our invention is to construct the dies so that the above operations can be performed by one stroke of the press in which the dies are mounted. The invention also relates to certain improvements in details of construction, which will be fully described hereinafter, reference being had 20 to the accompanying drawings, in which:

Fig. 1 is a side view of upper and lower dies made in accordance with our invention and used in the manufacture of horse shoes;

Fig. 2 is a transverse sectional view of the 25 upper die on the line 2—2, Fig. 3;

Fig. 3 is an inverted plan view of the upper die;

Fig. 4 is a plan view of the lower die;

Fig. 5 is a perspective view of a horse 30 shoe formed by our improved dies; and

Fig. 6 is a view illustrating a modification of the invention.

In the present instance, the horse shoe (Fig. 5) has a body portion *a*, a recessed toe 35 *b* at the forward end, and a series of heel calks *c* at the rear ends of the shoe. The recessed toe calk at the front of the shoe and the series of heel calks are formed by drop forging. The dies, which punch the 40 holes *d* in the blank, turn down the toe clip *e*, and straighten the blank, are made as follows:

1 is the lower die, recessed at 2 for the reception of a horse shoe blank. This die is 45 shaped at 3 to receive the turned down toe clip and is perforated at 4 for the passage of the punchings cut from the blank by the punches of the upper die. The blank is placed in the recessed portion of the lower die and is centered by a plunger 5 carried 50 by the upper die 6. The perforations 4, in the present instance, are in cylindrical blocks 7 detachably secured to the lower die by

screws 8 so that they can be replaced when injured.

Secured to the forward end of the upper die 6 by bolts 11 is a bearing 10 having a spindle 10^a on which is a roller 9 for bending the toe clip of a shoe. The plunger 5 is adapted to a cylindrical recess 15 in the upper die and is flanged at 16. The under side of the plunger is recessed at 12 and 13 for the reception of the calks *b* and *c* of the horse shoe blank. In the flange 16 of the plunger are passages 14 through which the punches 27 extend, which punch the nail holes *d* in the shoe blank. These punches 27 are located in sockets in the upper die and are held therein by screws 26.

17 are bolts, which extend through the 70 openings in the upper die and have reduced, threaded ends 18 that are screwed into threaded openings in the plunger 5. The heads 19 of the bolts are free to move in cavities 20 in the upper die. Surrounding 75 each bolt are coiled springs 21, which are located between the plunger 5 and the base of the recess 15 in the upper die. The flange 16 of the plunger is extended laterally, as shown in Fig. 3, and has seats 22 for heavy 80 coiled springs 23, which are adapted to seats 24 on the underside of the head 25 to which the upper die is secured. The springs 21 and 23 hold the plunger in the projected position so that, when the upper die is moved 85 towards the lower die, the plunger 5 will center the hot shoe blank on the lower die and will hold the blank in position.

While the punches, which are carried by the upper die, pass through openings 14 in the flange 16 of the plunger and punch the nail holes *d* in the blank, the punchings are forced through the openings 4 in the lower die. When the upper die recedes, the punches are carried with it, but the springs 90 expand and retain the plunger 5 on the blank. The pressure of the springs straightens the blank and, when the head and the upper die are raised to the full extent, the plunger 5 is withdrawn and the 100 finished horse shoe can be removed from the dies.

While a nest of four springs is shown and four bolts, it will be understood that the number of springs may be reduced, and, in 105 some instances, a single heavy spring, simi-

lar to the spring 23, may be located between the upper die and the plunger, and a heavy single bolt may be substituted for the bolts illustrated.

5. In Fig. 6 is illustrated a modification of the means for operating the plunger in place of the springs. The plunger 5^a is provided with suitable packing rings and in the recess 15 in the upper die is a cylinder 10 connected by a pipe to any fluid pressure means controlled by a valve.

It will be seen by our invention that after a blank has been formed by drop forging, it is heated and placed in position and the 15 entire set of nail holes is punched and the toe clip is bent into final shape simultaneously, and the shoe is straightened by the pressure of the springs before the upper die completes its return movement.

20. We claim:

1. The combination in dies used in the manufacture of horse shoes, of a lower die on which the horse shoe blank is mounted; an upper die; punches carried by the upper 25 die for punching nail holes in the blank; a plunger arranged to bear against the blank while the punches are forced therethrough, the plunger stripping the punches as they are returned; and means for resiliently holding the plunger, the pressure on the plunger in engagement with said blank during said stripping operation being sufficient to straighten the hot blank after the punches have been withdrawn from the blank.

35. 2. The combination of a lower die having a recess to receive a horse shoe blank; a spring-pressed plunger arranged to clamp the blank to the lower die; punches on each side of the upper die for simultaneously 40 punching all of the nail holes in the blank; and a roller carried by the upper die, said roller being arranged to bend a toe clip into final position as the die is punching the holes.

45. 3. The combination of a lower die arranged to receive a horse shoe blank; an upper die; a series of punches carried by the upper die and arranged to punch nail

holes in the blank; a roller, also carried by the upper die, for bending a toe clip into 50 final position; a plunger mounted in the upper die and arranged to bear upon the blank; bolts attached to the plunger and arranged to move freely in the upper die; and springs surrounding the bolts, said 55 springs tending to force the plunger onto the blank with such pressure as to straighten the blank after the nail holes have been punched.

4. The combination of a lower die shaped 60 to receive a horse shoe blank; a head; an upper die thereon; punches carried by the upper die for punching holes in the blank, the lower die having perforations through 65 which the punchings are projected; a roller for bending a toe clip, said roller being mounted in a bearing secured to the upper die; a flanged plunger mounted in the upper die and shaped to conform to the blank, the flange of the plunger having passages 70 through which the punches pass; bolts loosely connecting the plate to the upper die; springs surrounding the bolts; and springs on the outside of the upper die, said 75 springs being located between the flange of the plunger and the head, the springs acting to hold the plate to the blank while the blank is being punched and to straighten the blank after the punching operation.

5. The combination in dies used in the 80 manufacture of horse shoes, of a lower die recessed to receive the blank and having an edge over which the toe clip is bent; an upper die; a plunger therein, said plunger being shaped to conform to the shape of 85 the blank of the shoe and to hold and center the blank on the lower die during the punching operation; means for creating a pressure on said plunger and to straighten the shoe; punches, carried by the upper die, 90 arranged to project through passages in the plunger; and a roller, also carried by the upper die, arranged to bend a toe clip down against the lower die.

FRANK E. MERKLINGER.
SAMUEL R. LIMERICK.
